Primary Examiner — Abraham T Bahta(74) Attorney, Agent, or Firm — Crowell & Moring LLP(57) CLAIM

The ornamental design for a writing paper, as shown and described.

DESCRIPTION

The sole FIGURE is a front view of a writing paper showing our new design.

The broken lines are for illustrative purposes only and form no part of the claimed design. The writing paper has no appreciable thickness.

1 Claim, 1 Drawing Sheet
